UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed April 25, 1919, Serial No. 292,667. Renewed November 23, 1925.

My invention relates to mining machines.

It has for its object to provide an improved machine especially adapted to cutting in a plane or in any of a plurality of planes above the bottom of the machine. Another object of my invention is to provide such an improved machine adapted to cutting in a plurality of planes. A further object of my invention is to provide improved means especially adapted to use in connection with a standard type of bottom cutter, whereby the same may be adapted to use as above set forth. A still further object of my invention is to provide an improved machine of the character set forth adapted to use as a mounted cutter, i. e. one wherein the machine is mounted upon a truck and is adapted to perform the cutting operation while on the truck. These and other objects and advantages of my improved construction will, however, herein-after more fully appear.

In the accompanying drawings I have shown for purposes of illustration one embodiment which my invention may assume in practice.

In these drawings,—

Fig. 1 is a side elevation of a mounted cutter equipped with my improvement, the bar adjusting mechanism being shown in section to facilitate illustration.

Fig. 1^a is a detail sectional view of the clutch controlling mechanism.

Fig. 2 is a plan view of the construction shown in Fig. 1.

Fig. 3 is a transverse sectional view taken on line 3—3 of Fig. 1.

Fig. 4 is a diagrammatic plan view showing the machine in its different positions during the kerf cutting operation.

Fig. 5 is a diagrammatic side elevation showing the machine in different vertically adjusted positions.

Fig. 6 is a diagrammatic end view showing the machine in tilted position.

In this illustrative construction I have shown a mining machine frame or casing 1 of usual type slidable on its bottom and herein having a shoe 2 adapted to slide over the mine bottom, and a reversible motor 3 of any suitable type operatively connected through usual feeding mechanism (not shown) to a feed operating member 4 adapted when rotated by the motor to feed

the machine in a well known manner relative to flexible feeding means herein in the form of a flexible feeding member 5 in turn guided by usual guiding members 6 and having flexible feeding portions acting on the opposite ends of the machine frame. 55 60

In my improved construction, an operative driving connection, herein in the form of a chain 7, is connected to a part driven by the motor, herein to a sprocket 8, and extended above the shoe 2 and on opposite sides of the machine center line to the front end of the machine, where it engages a sprocket 9 herein having a lower sleeve 10 journaled on a vertical axis in a suitable bearing 11 herein carried on the front end of a longitudinally disposed bottom extension 12 on a removable front head member 13 and disposed over the front end of the shoe. Fixed to this sleeve 10, as by a spline 14, is an upright member, herein a shaft 15. 65 70 75 As shown, this shaft 15 has freely rotatable thereon at a point adjacent and above the sprocket 9, a gear 16, herein constantly meshing with a plurality of laterally and rearwardly disposed cooperating gears 17, herein fixed to the lower ends of laterally spaced upstanding feeding members 18, herein threaded and supported and rotatably mounted at their upper ends in top extensions 19 formed on the front head 13. 80 85

Carried upon these rotating threaded members 18, is a bracket 20, herein carrying nuts 21 adjustable on the threaded members and also being provided with guiding members 22, herein fitting around and guided by vertically disposed lateral extensions 23 formed on the sides of the head 13. This bracket 20, in turn, carries a cutter bar 24, herein integrally united therewith, and having rotatably mounted thereon a usual cutter chain 25 driven from a cutter chain driving sprocket 26, herein rotatable with the shaft 15 and vertically adjustable on a spline 27 extending longitudinally of the upper end of said shaft. Also, it will be observed 100 that I have provided a vertically adjustable clutch member 28 likewise splined on the shaft 15 and normally held in inoperative position by a spring 29, and adapted when depressed manually to engage with cooperating clutch teeth 30 formed on the hub of the gear 16, and thereby, through the gears 17 and the feed screw mechanism, raise the

bracket 20 and the bar bodily to vary the plane of operation. Attention is also directed to the fact that a stop, herein in the form of an annular flange 31 provides an abutment against which the clutch member 28 is normally held by its spring.

In a preferred embodiment of my invention, the machine is truck mounted. Herein it is slidably and removably mounted in a well known manner in a trough-like supporting and guiding member 32, herein fixed to and rotatable with an upper swivel plate 33 swiveled at 34 on a lower swivel supporting member or plate 35 and adapted to be held in any desired angular position relative to that plate by means of one or more locking pins 36. As shown, the plate 35 is also tiltably mounted on a horizontal pivot 37 located substantially in the center line of the machine and carried on a lower truck mounted member or plate 38. Thus it will be observed that the machine is adapted to be tilted laterally to either side to cooperate with the vertical adjusting mechanism to bring the bar 24 into any desired angle to the face. Herein, it will also be noted that the tilting means assume the form of supporting screws 39 pivotally connected at their upper ends at 40 to opposite sides of the plate 35 and adjustable by means of nuts 41 having operating hand wheels 42 thereon.

As in a usual construction, it will also be observed that the plate 38 is herein slidably longitudinally on guides 43 formed on a truck 44 and adapted to be locked in any desired position thereon, herein by pins 45. The mining machine 1 is, as usual in this type of machine, also provided with a gear 46 adapted to mesh with a cooperating gear 47 on a truck operatively connected in a usual manner to a truck driving shaft 48 which is in turn connected through truck wheel driving connections 49 to the truck wheels 50 so that, when the mining machine 1 is in a predetermined position upon the truck 44, the motor thereof may be utilized to propel the truck during the transport of the machine from one place to another.

In the operation of my improved construction it will be observed that whether the mining machine is carried upon a truck as shown, or used as a separate entity in a well known manner, the cutter bar thereof may be adjusted in such a manner as to vary the height of the kerf as desired, by, when necessary, simply connecting the clutch 28 to the clutch teeth 30 on the gear 16 and thereby raising or lowering the bar. More particularly, it will be noted that the bar may be adjusted vertically until the nuts 21 on the bracket 20 engage with the extension 19 on the front head 13, in which position it will be observed that the top of the bar is disposed substantially in the plane of the top of the machine so that the cutter chain will

cut a slightly higher kerf. Here also it will be noted that when the desired position of adjustment has been reached it is only necessary to release the clutch member 28, whereupon the spring 29 will force the same out of engagement with the clutch teeth 28 and into engagement with the abutment 31, thereby arresting further upward movement of the bar. Conversely, by reversing the motor 3, the direction of movement of the bar may be reversed and the same returned to its lowest position, wherein it is adapted to cut a kerf substantially midway of the top and bottom of the machine, this limit of travel being established by the engagement of the bar with the abutment 31 carried on the shaft 15.

In the use of my improved construction in connection with a truck mounted machine, it will be understood that the adjustment of the cutting mechanism is obtained substantially as described above. Here, however, it will be noted that when the cutter bar is disposed in any given horizontal plane, the plane of the same may be tilted as necessary through the manipulation of the hand wheels 42 in such a manner as to bring the bar into any desired angular variation of the positions obtained by the vertical adjusting mechanism. When in this position it will also be understood that the machine may then be operated on the truck to make the usual successive sumping, transverse, and withdrawal cuts, shown at A¹, A², and A³ in Fig. 4, to cut a kerf in advance of the machine, or may be swung laterally and locked as shown at A⁴ to make a longwall cut, all as in a usual manner. As the mechanism for so operating and adjusting the machine does not per se form a part of my present invention and is well known, a more specific description of the same is believed to be unnecessary.

As a result of my improved construction, it will be observed that a machine of standard construction may be adapted to use as an overcutter by removing the cutter bar and front head thereof and attaching my improved front head and adjustable cutter bar mechanism in lieu thereof. When thus equipped, it will also be observed that the machine may be utilized at will as an ordinary shortwall machine slidably upon its shoe or, if desired, as a mounted entry or longwall cutter, the cutter bar being adjustable when the machine is used in either of these relations, in such a manner as to enable kerfs to be inserted at will substantially in the plane of the top of the machine or in any one of a plurality of planes disposed beneath the top thereof and herein above the transverse center line thereof. Also, when the machine is mounted on its truck the bar is tilttable laterally when mounted, in such a manner as to vary the angle as

desired and thereby adapt it to cutting laterally pitching seams, dirt bands, etc. These and other advantages of my improved construction will, however, be clearly apparent 5 to those skilled in the art.

While I have in this application specifically described one embodiment which my invention may assume in practice, it is to be understood that this form is shown for illustrative purposes only and that the invention 10 may be modified and embodied in other forms without departing from its spirit or the scope of the appended claims.

What I claim as new and desire to secure 15 by Letters Patent is:

1. The combination with a mining machine comprising a casing 20 slidable on the mine bottom and disposed in planes adjacent the latter, of a cutter bar, and means for vertically adjusting the latter relative to said casing.

2. The combination with a mining machine comprising a casing slidable on the mine bottom and disposed in planes adjacent the latter, of a cutter bar, and means 25 for vertically adjusting the latter substantially into the plane of the top of said casing.

3. The combination with a mining machine comprising a casing slidable on the mine bottom and disposed in planes adjacent the latter, of a cutter bar, and means 30 for vertically adjusting the latter into a plurality of planes including a plane substantially at the top of said casing.

35 4. The combination with a mining machine comprising a casing slidable on the mine bottom and disposed in planes adjacent the latter, of a cutter bar, and means for vertically adjusting the latter into a plurality of planes above the transverse center line of said casing.

40 5. The combination with a flexibly fed laterally movable mining machine frame slidable on a mine bottom and disposed in planes adjacent the latter, of a cutter bar, and means for vertically adjusting the latter relative to said frame.

6. The combination with a flexibly fed laterally movable mining machine frame 45 slidable on a mine bottom and disposed in planes adjacent the latter, of a cutter bar, and means for vertically adjusting the latter substantially into the plane of the top of said frame.

55 7. The combination with a flexibly fed laterally movable mining machine frame slidable on a mine bottom and disposed in planes adjacent the latter, of a cutter bar, and means for vertically adjusting the latter into a plurality of planes including a plane substantially at the top of said frame.

8. The combination with a flexibly fed laterally movable mining machine frame 60 slidable on a mine bottom and disposed in planes adjacent the latter, of a cutter bar,

and means for vertically adjusting the latter into a plurality of planes above the transverse center line of said frame.

9. The combination with a mining machine head adapted to be applied to a mining machine casing slidable on the mine bottom and disposed in planes adjacent the latter, of cutting mechanism thereon including a cutter bar, and means thereon for vertically adjusting the plane of said bar. 70

10. The combination with a mining machine slidable on the mine bottom and comprising a casing disposed in planes adjacent the mine bottom, of a front head, a cutter bar supported thereon, a cutter chain on said bar, cutter chain driving mechanism, mechanism for adjusting said bar vertically on said head, and cooperating bar guiding means. 75

11. The combination with a mining machine slidable on the mine bottom and comprising a casing disposed in planes adjacent the mine bottom, of a front head, a cutter bar vertically adjustable thereon, a cutter chain on said bar, mechanism for driving said chain in any position of adjustment, and cooperating guiding means between said bar and head. 85

12. The combination with a mining machine comprising a casing disposed in planes adjacent the mine bottom, of a front head therefor having a lower longitudinally disposed extension adapted to engage the mine bottom, a cutter bar supported on said extension, and means for adjusting said bar 90 into a plurality of vertical positions thereon. 95

13. In a kerf cutting mechanism, the combination including a machine frame, a vertically disposed power driven member, a cutter bar through which the same extends, mechanism for adjusting said bar vertically along said member, and a clutch controlling the connection of said adjusting mechanism to said member. 105

14. In a kerf cutting mechanism, the combination including a machine frame, a plane cutter bar, a power driven member supported on said frame in a position wherein it is perpendicular to the plane of said bar at a point between the ends of the bar, mechanism for adjusting said bar bodily in a direction longitudinal of said member relative of the latter, and mechanism controlling the connection of said adjusting mechanism to said member. 110

15. In a kerf cutting mechanism, the combination including a machine frame, cutting mechanism supported thereon for bodily adjustment relative thereto, a power driven member supported on said frame in a 115 position perpendicular to said cutting mechanism, actuating mechanism for said cutting mechanism driven by said member, and means for adjusting said cutting mechanism bodily in a direction longitudinal of said 120

125 planes adjacent the latter, of a cutter bar, 130

member relative to the latter actuatable by said member.

16. In a kerf cutting mechanism, the combination including a machine frame, a cutter chain supporting cutter bar supported thereon for bodily adjustment relative thereto, a power driven member supported on said frame in a position perpendicular to the orbit of said cutter chain at a point within 5 such orbit, a cutter chain driving sprocket on said power driven member, and means for adjusting said cutter bar bodily in a direction longitudinal of said member including a controlling clutch coaxial with said member.

17. The combination with a kerf cutting mechanism including a cutter bar and a power driven member, mechanism for adjusting said bar vertically relative to said 20 member, and an automatically releasable clutch controlling the connection of said adjusting mechanism to said member.

18. In combination, a truck, vertically adjustable kerf cutting mechanism disposable 25 in a plurality of parallel planes, and a mining machine carrying said vertically adjustable kerf cutting mechanism and operable on said truck or as a separate entity when removed therefrom.

19. The combination with a mining machine comprising a casing slidable on the mine bottom and disposed in a plurality of planes adjacent the latter, of an upright cutter chain driving shaft on said casing, a 30 cutter bar thereon, a cutter chain on said bar, and means for adjusting said bar vertically on said shaft.

20. The combination with a mining machine comprising a casing slidable on the mine bottom and disposed in planes adjacent the latter, of a cutter bar, a bar carrying bracket adjustable vertically on the front end of said casing, and mechanism for adjusting said bracket.

21. In combination with kerf cutting mechanism, a truck, a swivel support adjustable at will to different angular positions between said mechanism and said truck and movable longitudinally of the latter, and means for tilting said swivel support into a plurality of operative positions about an axis disposed along the longitudinal center line of said truck.

22. In combination with a cutter bar mechanism, a truck, a bar supporting platform thereon movable longitudinally of the latter, and operative connections disposed between the platform and the truck and movable longitudinally relative to the truck for tilting the platform into a plurality of operative positions about an axis disposed substantially in the longitudinal center line of the truck.

23. In combination, kerf cutting mechanism, a truck, a laterally tiltable support for

the mechanism pivotally mounted on an axis disposed substantially in the longitudinal center line of the truck, and adjustable co-operating supporting means on opposite sides of the pivot, said support and said adjustable co-operating supporting means being movable longitudinally relative to the truck. 70

24. The combination with a mining machine casing slidable on the mine bottom, of cutter mechanism including a cutter bar and 75 a cutter chain and vertically adjustable relative thereto, means for rotating said cutter chain, and means operatively connectable therewith for adjusting said bar.

25. The combination with a mining machine comprising a casing slidable over and disposed in planes adjacent the mine bottom, of guiding means carried at the sides thereof, a cutter bar carrying bracket guided by 80 said guiding means, a cutter bar, a cutter 85 chain carried on said bar, means for driving said cutter chain, and means for adjusting said bracket including an element coaxial with said cutter chain driving member.

26. The combination with a mining machine casing, of a shoe adapted to engage the mine bottom and disposed beneath the casing, a driving member journaled on the front end of said shoe, a cutter bar carrying bracket movable vertically in guided relation with said machine and driving member, a cutter chain on said bracket, and means for driving said chain and adjusting said bracket. 90

27. The combination with a mining machine comprising a casing slidable on the mine bottom and disposed in planes adjacent the latter, of cutter mechanism including a cutter bar and a cutter chain vertically 100 adjustable relative thereto, means for rotating said cutter chain, vertically adjusting mechanism including a plurality of feed members for said bar, and means for rotating said members. 105

28. The combination with a mining machine comprising a casing disposed in planes adjacent the mine bottom, of an upright cutter chain driving shaft journaled on the front end thereof vertically adjusting mechanism including a plurality of upright feed 110 screws carried on the front end thereof, a cutter bar carrying bracket adjustable relative to said screws, and means for rotating said screws to vary the elevation of said bracket including an element passing through 115 said bar. 120

29. The combination with a mining machine comprising in casing disposed in planes adjacent the mine bottom, of an upright cutting mechanism driving shaft journaled on 125 the front end thereof, a plurality of upright feed screws carried on the front end thereof, a cutter bar carrying bracket adjustable relative to said screws, and means including a clutch for connecting said up- 130

right shaft to rotate said screws to vary the elevation of said bracket.

30. In combination, a truck, a mining machine thereon adapted to slide on the mine bottom and having kerf cutting mechanism disposable in a plane adjacent the top of said machine or in different planes parallel thereto, and means for moving said machine during cutting relative to said truck or relative to the bottom when removed from said truck.

31. In combination, a truck, a mining machine thereon adapted to slide on the mine bottom and having vertically rectilinearly adjustable kerf cutting mechanism disposable substantially in the plane of the top of said machine, and means for moving said machine during cutting relative to said truck or relative to the bottom when removed from said truck.

32. In combination, a truck, a mining machine adjustably mounted thereon and adapted to slide on the mine bottom and having vertically rectilinearly adjustable kerf cutting mechanism, and flexible feeding means for selectively moving said machine during cutting relative to said truck or relative to the bottom when removed from said truck.

33. In combination, a truck, kerf cutting mechanism thereon including a cutting element and a driving motor therefor, a support for said kerf cutting mechanism presenting a swivel therefor permitting adjustment thereof as a whole at will to different positions and movable about a horizontally disposed pivot located beneath the swivel of said kerf cutting mechanism and longitudinally of said truck between the sides of the latter, and means for tilting said support about its pivot and supporting the same in its different positions of adjustment.

34. In combination, a mining machine truck, swiveled kerf cutting mechanism thereon including a cutter bar and a cutter chain thereon and a driving motor for said chain, means for tilting said mechanism as a whole relative to said truck including a swivel carrying support for said cutting mechanism movable about a horizontally disposed pivot and cooperating adjusting means, and self-contained means for moving said kerf cutting and tilting means longitudinally of said truck relative to the latter.

35. In combination, a mining machine truck, a support non-rotatably carried thereon but movable longitudinally therewith, a cooperating support pivoted on said support on a longitudinal axis, means for adjusting said cooperating support about its axis in either direction from the horizontal, and kerf cutting mechanism on said cooperating support including a cutting element and a driving motor therefor.

36. In combination, a mining machine

truck, a support non-rotatably carried thereon, a cooperating support pivoted on said support on a horizontal longitudinal axis substantially midway between the sides of the truck, means for adjusting said cooperating support about its axis, and kerf cutting mechanism swiveled on said cooperating support for adjustment at will as a whole relatively thereto and including a cutting element and a driving motor therefor.

37. In combination, a mining machine truck, a support non-rotatably carried thereon, a cooperating support pivoted on said support on a horizontal longitudinal axis substantially midway between the sides of the truck, means for adjusting said cooperating support about its axis, kerf cutting mechanism swiveled on said cooperating support for adjustment as a whole relatively thereto and including a cutting element and a driving motor therefor, and means for holding said kerf cutting mechanism in different angular relations to said cooperating support.

38. In a mining machine, a mining machine truck, a support non-rotatably carried thereon, a cooperating support tiltable on said first mentioned support about an axis extending longitudinally of the truck between the sides of the latter, tilting means between said supports, and a complete mining machine capable of cutting on its own bottom disposed on said cooperating support and tiltable therewith.

39. In a mining machine, a mining machine truck, a support non-rotatably carried thereon, a cooperating support tiltable on said first mentioned support about an axis extending longitudinally of the truck between the sides of the latter, tilting means between said supports, a complete mining machine capable of cutting on its own bottom on a mine bottom swiveled on said cooperating support and tiltable therewith, and means for holding said mining machine in different angular relations with respect to said cooperating support.

40. In a mining machine, a mining machine truck, a support non-rotatably carried thereon, a cooperating support tiltable laterally about a longitudinal pivot carried on said first mentioned support, tilting means on opposite sides of said pivot and between said supports, a complete mining machine capable of cutting on its own bottom on a mine bottom swiveled on said cooperating support and tiltable therewith, and means for holding said mining machine in different angular relations with respect to said cooperating support.

41. In a mining machine, a mining machine casing slidably supported on the mine bottom and disposed in planes adjacent the latter, a cutter bar carried on one end thereof and disposed in a plane intersecting

said casing; and means on said casing for adjusting said bar into a parallel plane.

42. In a mining machine, a mining machine casing slidably supported on the mine bottom and disposed in planes adjacent the latter, a cutter bar carried on one end thereof and disposed in a horizontal plane intersecting said casing, and means on said casing for adjusting said bar into a different plane parallel to the bottom of said casing.

43. In a mining machine, a mining machine casing slidably supported on the mine bottom and disposed in planes adjacent the latter, a cutter bar carried on one end thereof and disposed in a horizontal plane intersecting said casing, and means on said casing for adjusting said bar into a different horizontal plane substantially coinciding with one of the surfaces of said casing.

44. In a mining machine, a mining machine casing slidably supported on the mine bottom and disposed in planes adjacent the latter, a cutter bar carried on one end thereof, and means on said casing for adjusting said bar into a horizontal plane between the top and bottom of said casing or into a horizontal plane at a different vertical elevation from said horizontal plane.

45. In a mining machine, a mining machine casing disposed in planes adjacent the mine bottom and adapted to slide on its own bottom on a mine bottom, a cutter bar carried on one end thereof, and means on said casing for adjusting said bar into a horizontal plane between the top and bottom of said casing or into a horizontal plane above said plane.

46. In a mining machine, a mining machine casing disposed in planes adjacent the mine bottom and adapted to slide on its own bottom on a mine bottom, a cutter bar carried at one end of said casing and disposed in a plane intersecting said casing, and means on said casing for adjusting said cutter bar into a different plane parallel to said plane and below the latter.

47. In a mining machine, mining mechanism including a machine casing slidable relative to a mine bottom and disposed in planes adjacent the latter and having a cutter chain carrying cutter bar on one end of said casing, means for adjusting said bar into positions in a plurality of horizontal planes, and flexible feeding means for propelling said bar laterally to form a kerf in a face acting in a plane below the uppermost position of said bar.

48. In a mining machine, mining mechanism including a mining machine casing slidable on a mine bottom and disposed in planes adjacent the bottom and having a cutter chain carrying cutter bar carried on one end of said casing, means for adjusting said bar into positions in a plurality of horizontal planes, and flexible feeding

means for propelling said bar laterally to form a kerf in a face including a guiding member disposed adjacent said bar and beneath the uppermost position thereof.

49. The combination with a mining machine comprising an elongated frame and a cutter bar and slidable on a mine bottom and disposed in horizontal planes adjacent the latter, of means on said machine whereby while said frame is retained of the same height said bar may be disposed for cutting in different horizontal planes relative to the surface of said frame which engages the mine bottom with each of said planes intersecting the frame substantially throughout the length of the latter.

50. The combination with a mining machine comprising an elongated frame and a cutter bar and slidable on a mine bottom and disposed in horizontal planes adjacent the latter, of means on said machine whereby while said frame is retained of the same height said bar may be disposed for cutting in different horizontal planes relative to the surface of said frame which engages the mine bottom with each of said planes intersecting the frame substantially throughout the length of the latter, and supporting means whereby said machine may be mounted for cutting on a higher level.

51. The combination with a mining machine comprising an elongated frame and a cutter bar and slidable on a mine bottom and disposed in horizontal planes adjacent the latter, of means on said machine whereby while said frame is retained of the same height said bar may be disposed for cutting in different horizontal planes relative to the surface of said frame which engages the mine bottom with each of said planes intersecting the frame substantially throughout the length of the latter, and flexible feeding mechanism operable to feed said machine laterally in any position of said bar.

52. The combination with a mining machine comprising an elongated frame and a cutter bar and slidable on a mine bottom and disposed in horizontal planes adjacent the latter, of means on said machine whereby while said frame is retained of the same height said bar may be disposed for cutting in different horizontal planes relative to the surface of said frame which engages the mine bottom with each of said planes intersecting the frame substantially throughout the length of the latter, and flexible feeding mechanism including flexible feeding portions acting on the opposite ends of said frame and operable to feed said frame laterally in any position of said bar.

53. The combination with a mining machine comprising an elongated frame and a cutter bar and slidable on a mine bottom and disposed in horizontal planes adjacent the latter, of means on said machine where-

5 by while said frame is retained of the same height said bar may be disposed for cutting in different horizontal planes relative to the surface of said frame engaging the mine bottom each of which intersects said frame substantially throughout the length of the latter, and flexible feeding mechanism operable to feed said machine laterally and in any position of said bar exerting a lateral 10 pull in a plane below the uppermost position of said bar.

15 54. The combination with a mining machine comprising an elongated frame and a cutter bar and slidable on a mine bottom and disposed in horizontal planes adjacent the latter, of means on said machine whereby while said frame is retained of the same height said bar may be disposed for cutting in different horizontal planes relative to the 20 surface of said frame engaging the mine bottom each of which intersects said frame substantially throughout the length of the latter, and flexible feeding mechanism including flexible feeding portions acting on 25 the opposite ends of said frame and operable to feed said frame laterally in any position of said bar while pulling in a plane below the uppermost position of said bar.

30 55. The combination with a mining machine slidable on a mine bottom and disposed in planes adjacent the latter, of cutting mechanism including a cutter chain carrying cutter bar projecting from and carried by one end of said machine and a cutter 35 chain driving sprocket at the end of said machine from which said bar projects, flexible feeding mechanism on said machine including a feed operating member adapted to cooperate directly with flexible feeding 40 means and disposed adjacent the other end of said machine, a motor on said machine, and means for driving said sprocket from the end of said motor toward said feed operating member.

45 56. In combination with a mining machine slidable on a mine bottom and disposed in planes adjacent the latter, of cutting mechanism including a cutter chain carrying cutter bar projecting from and carried by one end of said machine and having 50 a cutter chain driving sprocket at the end of said machine from which said bar projects, flexible feeding mechanism on said frame including a feed operating member adapted to cooperate directly with flexible feeding 55 means and disposed adjacent the other end of said machine, a longitudinally extending horizontal motor on said machine, and means for driving said sprocket from the end of said motor which is nearer said feed operating member.

60 57. In combination with a mining machine frame slidable on a mine bottom and disposed in planes adjacent the latter, of cutting mechanism including a cutter chain

carrying cutter bar rigidly connected to and projecting longitudinally from one end of said frame and a cutter chain driving sprocket at said end, flexible feeding mechanism on said frame including a feed operating member adjacent the other end of the machine and flexible feeding portions acting on the opposite ends of said frame, a horizontally disposed motor on said frame on the opposite side of said sprocket from said 70 bar, and means for driving said sprocket from the end of said motor toward said feed operating member.

75 58. The combination with a mining machine comprising a frame slidable on a mine bottom and disposed in planes adjacent the latter and having a horizontal motor thereon and cutting mechanism thereon including a rigidly connected longitudinally extending cutter chain carrying cutter bar and a cutter 80 chain driving sprocket, said sprocket being located in front of said motor and driven thereby, of means for feeding said machine laterally driven by said motor and including power operated and controlled flexible feeding 85 portions acting on the opposite ends of said machine frame and having an advance portion acting in a plane between the mine bottom and the top of said bar.

90 59. The combination with a mining machine slidable on a mine bottom and having a longitudinally extending horizontal motor thereon and cutting mechanism including a longitudinally extending rigidly connected cutter chain carrying cutter bar and a cutter 95 chain driving sprocket in front of said motor, of means driven by said motor for feeding said machine laterally including feed operating means and power operated and controlled flexible feeding portions acting on 100 the opposite ends of the machine body and having an advance portion acting in a plane between the mine bottom and the top of said bar, and means for driving said cutter chain driving sprocket from the end of said motor 105 adjacent the feed operating member.

110 60. The combination with a mining machine slidable on a mine bottom and having a longitudinally extending horizontal motor thereon and cutting mechanism including a longitudinally extending rigidly connected cutter chain carrying cutter bar and a cutter 115 chain driving sprocket in front of said motor, of means for feeding said machine laterally including feed operating means and flexible feeding portions acting on the opposite ends of the machine body and having an advance portion acting in a plane between the mine bottom and the top of said bar, means for driving said cutter chain driving sprocket from the end of said motor 120 nearer the feed operating means, and supporting means whereon said machine may be supported at will for cutting in a higher 125 plane.

61. In a mining mechanism, in combination, a cutter bar disposable for cutting only in planes substantially parallel to a mine bottom, and means for supporting said bar during cutting at different heights with respect to the bottom including a casing slideable directly on the mine bottom and having horizontal bounding surfaces to which the bar is parallel at all times during cutting.

62. A mining machine comprising, in combination, a casing slideable directly on a mine bottom, a plane cutter bar projecting from said casing in parallelism with one surface of said casing, and means whereby said bar may be disposed to cut a kerf whose upper bounding surface is at a distance from the bottom substantially equal to the height of the casing and a different kerf below said first mentioned kerf while constantly remaining in parallelism with the first mentioned surface of the casing.

63. In a kerf cutting mechanism, the combination including a machine frame, a vertically disposed power driven member, a cutter bar through which the same extends, mechanism for adjusting said bar vertically along said members including screw means parallel to said vertically disposed power driven member and disposed at the opposite side of the latter from the free end of said cutter bar, and a clutch controlling the connection of said adjusting mechanism to said member.

64. In a kerf cutting mechanism, the combination including a machine frame, a vertically disposed power driven member, a cutter bar through which the same extends, mechanism for adjusting said bar vertically along said member including screw means parallel to said vertically disposed power driven member and having only motion of rotation, and a clutch controlling the connection of said adjusting mechanism to said member.

65. In a kerf cutting mechanism, the combination including a machine frame, a plane cutter bar, a power driven member supported on said frame in a position wherein it is perpendicular to the plane of the bar at a point between its ends, and power mechanism for adjusting said bar bodily in a direction longitudinal of said member including a screw rotating on a stationary axis and a nut movable therealong, and mechanism controlling the connection of said adjusting mechanism to said member.

66. In a kerf cutting mechanism, the combination including a machine frame, a plane cutter bar, a power driven member supported on said frame in a position wherein it is perpendicular to the plane of the bar at a point between its ends, and power mechanism for adjusting said bar bodily in a direction longitudinal of said member including a screw rotating on a stationary

vertical axis and mechanism controlling the connection of said adjusting mechanism to said member.

67. In a kerf cutting mechanism, the combination including a machine frame, cutting mechanism supported thereon for bodily adjustment relative thereto, a power driven member supported on said frame in a position perpendicular to said cutting mechanism, actuating mechanism for said cutting mechanism driven by said member, and means for actuating said cutting mechanism bodily in a direction longitudinal of said member including a screw rotatable on an axis parallel to the axis of said power driven member and arranged at a point at the opposite side of the latter from the free end of said cutting mechanism.

68. In a mining apparatus, a machine frame slideable on its bottom over a mine bottom and having a motor intermediate its ends, cutting mechanism including a cutter bar on said frame wholly at one end of said motor, a feed operating member at the other end of said motor, and actuating connections for said cutting mechanism extending from the end of the frame at which said feed operating member is disposed.

69. In a mining apparatus, a machine frame slideable on its bottom over a mine bottom during cutting and having a motor intermediate its ends, cutting and machine feeding mechanisms respectively at opposite ends of said motor, and driving connections for one of said mechanisms extending parallel to said motor and to a point at the opposite end of said motor from said mechanism.

70. In a mining apparatus, a machine frame comprising a motor intermediate its ends, cutting mechanism mounted for bodily vertical rectilinear adjustment relative to said motor and frame at one end of the latter, and means including a power connection extending to the opposite end of said motor for effecting such bodily vertical adjustment.

71. In a mining apparatus, a machine frame comprising a motor intermediate its ends, cutting mechanism mounted for bodily rectilinear adjustment relative to said frame and motor at one end of the frame, and means including a power connection extending to the opposite end of said motor for effecting such bodily adjustment of said cutting mechanism.

72. In a mining apparatus, cutting apparatus including a cutter bar carrying orbitally moving cutting elements and mounted for bodily movement about an axis parallel to the plane of the bar, for swinging movement in its planes, and for bodily movement towards and from said axis, a motor for effecting orbital movement of said cutting elements and bodily movement of itself and of said cutter bar, and a power connection ex-

tending from the end of said motor remote from said cutter bar for effecting circulation of said cutting elements.

73. In a mining apparatus, cutting apparatus including a cutter bar carrying orbitally moving cutting elements and mounted for bodily movement about an axis parallel to the plane of the bar, for swinging movement in its planes, and for bodily movement 5 towards and from said axis, a motor for effecting orbital movement of said cutting elements and bodily movement of itself and of said cutter bar, and a power connection extending from the end of said motor remote 10 from said cutter bar for effecting bodily movement of said cutter bar relative to 15 said axis.

74. In a mining apparatus, cutting apparatus including a cutter bar carrying orbitally moving cutting elements and mounted for bodily movement about an axis parallel to the plane of the bar, for swinging movement in its planes, and for bodily movement towards and from said axis, a motor for effecting orbital movement of said cutting elements and bodily movement of itself and of said cutter bar, and a power connection extending from the end of said motor remote 20 from said cutter bar for effecting circulation of said cutting elements and for effecting 25 bodily movement of said cutter bar relative to said axis.

In testimony whereof I affix my signature.
MORRIS P. HOLMES.

CERTIFICATE OF CORRECTION.

Patent No. 1,670,153.

Granted May 15, 1928, to

MORRIS P. HOLMES.

It is hereby certified that error appears in the printed specification of the above numbered patent requiring correction as follows: Page 1, line 5, strike out the words "above the bottom of the machine" and insert the same after the word "planes" in line 8; page 3, line 56, claim 7, for the misspelled word "lateraly" read "laterally"; same page, line 101, claim 12, for the misspelled word "pluraltiy" read "plurality"; and line 118, claim 14, for "of" read "to"; page 4, line 114, claim 28, after the word "thereof" insert a comma; page 5, line 73, claim 36, for the misspelled word "adjsusment" read "adjustment"; page 8, line 27, claim 63, for "members" read "member"; and that the said Letters Patent should be read with these corrections therein that the same may conform to the record of the case in the Patent Office.

Signed and sealed this 10th day of July, A. D. 1928.

(Seal)

M. J. Moore,
Acting Commissioner of Patents.
